By her Attorney,

Thomas H. Dodge

UNITED STATES PATENT OFFICE.

LAVINIA H. FOY, OF WORCESTER, MASSACHUSETTS.

IMPROVEMENT IN CORSETS.

Specification forming part of Letters Patent No. **39,908**, dated September 15, 1863.

To all whom it may concern:

Be it known that I, LAVINIA H. FOY, of the city and county of Worcester, and State of Massachusetts, have invented certain new and useful Improvements in Combined Corset, Shoulder-Brace, and Skirt-Supporter; and I do hereby declare that the following is a full, clear, and exact description of the same, reference being had to the accompanying drawings, forming a part of this specification, and in which—

Figure 1 represents a front view of the same. Fig. 2 represents a section on line A B, Fig. 1, and Figs. 3, 4, 5, 6, 7, 8, and 9 represent detached parts.

In the drawings, A represents the main part which forms the body B. A long, narrow piece is cut from the lower edge across the back and as far toward the front as it is desirable that the rim should extend, as seen at a a, Fig. 4, the rim C itself being cut separately and nearly in the form of a semicircle, as seen at C', Fig. 5. The inner edge b, and ends c c, of the rim C are stitched to the lower part, A', of the waist, and the hoop D inserted in the outer edge thereof. The straps E E are in two parts, the front and back parts of which are connected by elastics d d. The shoulder-brace F is curved to fit the arm, broad on the shoulder, as seen at e, and gradually tapering to the other extremity, f, where it is fastened by a hook, g. The shoulder-brace is so made that it can be readily detached from the

straps E, eylet-holes h being formed in each for the reception of a fastening-tape or other proper connecting device. Slits a' a' are made in the front part of A, and gores G G inserted to give the proper fullness for the bosom.

In Figs. 4, 5, 6, 7, and 8 the parts are shown as they appear before the article is made up.

In the drawings, i i represent metal caps, which may be attached so as to cover the ends of the hoop D. They are made with two prongs or points, one of which is seen at i' in Fig. 9. After the hoop D has been inserted in the rim C these metal caps may be placed over the cloth which covers the ends of the hoop D, as shown in the drawings, and their prongs or points i' forced through the cloth—one on each side of the hoop—and their projecting ends (see Fig. 9) then bent or riveted down.

Having described my improvements, what I claim as my invention, and desire to secure by Letters Patent, is—

1. Forming the rim C by cutting out a piece from the lower part, A', of the waist A, as seen in Fig. 4 at a a, and inserting the semicircle piece C', Fig. 5.

2. The combination, with the waist A, and straps E E, of detachable shoulder-braces F.

LAVINIA H. FOY.
